UNITED STATES PATENT OFFICE.

EDMUND C. MORGAN, OF NEW YORK, N. Y.; OLIVE EUGENIE MORGAN EXECUTRIX OF SAID EDMUND C. MORGAN, DECEASED.

MINING AND LOADING APPARATUS.

Application filed June 23, 1929. Serial No. 291,212.

My invention relates to mining and loading machines, and one of the objects thereof is the provision of improved and efficient apparatus of this type.

More particularly it is the object of the present invention to provide improved mechanism for operating splitting tools to dislodge coal from an arcuate mine wall in position to be automatically received by loading apparatus and transferred automatically to a mine car on a track in the mine chamber back of the mining and loading apparatus.

Another object of the present invention is the provision of supplemental conveyer mechanism arranged to travel arcuately along a portion of the arcuate mine wall to move the dislodged material into position to be received by the main conveyer of the loading apparatus.

Another object of the invention is the provision in a mining and loading machine of supplemental conveyer mechanism and splitting tools on opposite sides of the machine arranged to occupy folded positions at one side of the machine while those on the other side are in operation.

Other objects of the invention will appear hereinafter, the novel combinations and features being set forth in the appended claims.

Referring to the accompanying drawings, Fig. 1 is a plan view of my combined mining and loading machine;

Fig. 2 is an elevational view of the combined mining and loading machine with the splitting or digging tools in operating positions and a portion in section, on the line 2-2 of Fig. 1;

Fig. 3 is an enlarged sectional elevation illustrating the anchoring mechanism for the splitting tools;

Fig. 4 is an enlarged plan view of one of the supplemental conveyers;

Fig. 5 is a sectional elevation of Fig. 4 on the line 5-5, looking in the direction of the arrows;

Fig. 6 is a horizontal section taken through a portion of one of the splitting tool arms to show the flexible anchorage for one of the draft ropes;

Fig. 7 is a sectional side view on the line 7-7 of Fig. 3;

Fig. 8 is a sectional plan view on the line 8-8 of Fig. 3; and

Fig. 9 is a diagrammatic view of the electric circuits and connections for controlling

the application and release of the anchoring mechanism for the splitting or digging tools.

Referring to Figs. 1 and 2, it will be seen that the main frame 10 is mounted on tractor mechanism comprising endless belts 11 and 12 for advancing the mining and loading machine along the mine floor in advance of the track 13. While the rear portion of the main frame 10 is preferably elevated from the floor, the forward portion is adapted to rest directly on the floor as indicated at 14 in Fig. 2, so that when the vertical roof jacks are operated, as hereinafter described, the pressure at the floor will be exerted over that portion of the frame designated 14 and not on the tractor mechanism.

I prefer to use tractor mechanism operatively connected to the motor 15 so as to distribute the weight of the mining and loading machine over a wider area during movement of the machine over the mine floor to advanced positions. The rear end of the motor shaft is provided with a worm 16 in mesh with the worm gear 17 at the center of the transverse shaft 18. Therefore, when the clutch 19 is thrown in by means of the lever 20, power may be transmitted from the motor 15 to the tractor mechanism to move the mining and loading machine either forwardly or rearwardly depending upon the direction of the motor as controlled by well known electric controlling mechanism.

At the forward end of the motor 15 is another worm 21 meshing with a worm gear 22 at the center of the transverse shaft 23 the ends of which are provided with worms 24 and 25 meshing respectively with the worm gears 26 and 27 on the vertical shafts 28 and 29.

Rigidly connected to the base plate 14 is a conveyer frame comprising upright spaced-apart side walls 30 and 31 between which is adapted to travel an endless conveyer 32. The forward end of the conveyer frame is provided with a beveled or scooping portion 33 which is adapted to rest on the mine floor adjacent the upright mine wall from which the material is to be mined. It will be seen by referring to Fig. 2 that the conveyer 32 is inclined upwardly and rearwardly so as to extend over the top of the motor 15 and to the rear thereof. The rear end of the conveyer frame is secured to the frame of the motor 15 by means of the spaced-apart bracket arms 34 and 35, as shown in Figs. 1 and 2. 110

The endless conveyer 32 may be driven by sprockets 36 operated by a separate electric motor illustrated diagrammatically at 37 in Fig. 2.

- 5 As shown in Fig. 2, the main frame 10 is provided with a rearward extension 38 to which is pivoted at 39 a deep storage hopper 40 which is connected to the forward end of the rear conveyer frame 41. An endless conveyer 42 is mounted in the conveyer frame 41 and extends to the bottom of a hopper 40 above the pivot 39. The endless conveyer 42 may be driven by sprockets 43 to which is connected an electric motor illustrated diagrammatically at 44 in Fig. 2. The conveyer frame 41 is provided with a forwardly extending central arm 45 which is pivoted at 46 to the U-shaped frame 47 secured to the bracket arms 34 and 35. The pivot 46 is 10 in vertical alinement with the pivot 39 and the rear conveyer may therefore be swung on the vertical axis through the pivots 39 and 46, and by reason of the U-shaped frame 47 and the shape of the hopper 40, delivery 15 communication between the conveyer 32 and the conveyer 42 may be maintained for the various lateral positions of the rear conveyer. The rear conveyer may be extended into a mine car 48 on the track 13 in rearward alinement with the main frame 10, or into a mine car on the track at either side of the track 13 20 and parallel thereto.

At the forward end of the main conveyer frame at opposite sides of the scoop 33 are 25 pivoted at 49 and 50 supplemental arcuate conveyers 51 and 52 each comprising an arcuate frame with an endless flight conveyer mounted thereon and connected for operation to driving mechanism mounted on the vertical side plates 30 and 31. Since these supplemental conveyers are alike in construction a description of one will be sufficient.

Referring to Figs. 1 and 4, it will be seen 30 that the arcuate swinging supplemental conveyer comprises an arcuate frame 53. This frame is provided with a driving sprocket illustrated at 54 in Fig. 4 at one end of the frame 53 and with an idler illustrated at 55. An endless sprocket chain 56 is mounted in the frame 53 to be guided along the guideway 57, and on the forward side along the guideway 58. The front side of the frame 53 or that side which faces the mine wall, as 35 shown in Fig. 1, is provided with only one lower plate 59 which is adapted to rest flat on the floor, as shown in Fig. 2. The endless chain 56 is provided with laterally extending flights 60 which slide over the upper surface 40 of the arcuate plate 59 in the direction of the arrow 61 so as to move material along the arcuate base of the mine wall toward the receiving end of the conveyer 32. It should be understood that the supplemental arcuate conveyers 51 and 52 operate in opposite direc- 45

tions so as to each move material along the mine wall toward the scoop 33.

By referring to Fig. 5, which is a sectional view on line 5—5 of Fig. 4 looking in the direction of the arrows, it will be seen that the driving sprocket 54 is connected by means of the vertical shaft 50' to the spur gear 62 meshing with the spur gear 63 on the vertical shaft 64 and carrying a bevel gear 65 which meshes with the bevel gear 66 on the horizontal shaft 67.

It should be noted that the shaft 67 is the lower transverse shaft of the conveyer 32 and carries at its ends a pair of sprockets, one of which is shown at 68 in Fig. 5 for driving one of the chains of the conveyer, as shown at 69 in Fig. 4. The frame 31' shown in Fig. 5 is an extension of the frame 31 rigidly connected to the latter, and the supplemental conveyer 53 is pivotally connected 50 to the extension 31', as shown at 50 in Fig. 5, so as to swing on the upright axis of the shaft 50'. By means of this arrangement power may be transmitted to each of the supplemental conveyers whenever the main conveyer 90 55 32 is driven irrespective of the positions to which the supplemental conveyers are swung. In order to permit the outer portions of the supplemental conveyers to rest flat on the floor, as shown in Fig. 2, the frame 53 may 95 be bent downwardly as illustrated at 70 in Figs. 4 and 5. This arrangement also facilitates movement of the material from the floor to and over the scooping end 33 of the main 100 conveyer frame.

By referring to Figs. 2 and 3, it will be seen that the worm gear 27, which is connected to be driven by the motor 15 through the worm gearing 21, 22, the shaft 23 and worm 25, is loosely mounted on the vertical hollow shaft 71, the lower end of which rotates in a bearing in the base plate 14 and the upper end of which rotates in bearings 72 and 73 secured to the outer wall of the vertical plate 31 of the main conveyer frame.

Intermediate the ends of the hollow shaft 71 is splined a clutch element 74 adapted to be operated by means of a lever 75 pivoted at 76 to the plate 31. The worm gear 27 carries at its upper side a clutch element 77 adapted to be engaged by the clutch element 74. Therefore, when the motor 15 is operated and the clutch 74, 77 thrown in, motion will be transmitted to the vertical hollow shaft 71.

At the upper end of the shaft 71 is a rope drum 78 and at the lower end of said shaft is another rope drum 79. The ends of the rope 80 are secured to the rope drum 78 and the intermediate loop portion extends around the direction pulleys 81 and 82 to and around a flexible anchorage pulley 83 mounted in a pulley block 84 which is pivoted at 85 in a horizontal recess 86 at the outer end of an arm 87 which carries a coal splitting tool 88, as shown in Fig. 3. The direction pulleys 81 120 125 130

and 82 are mounted loosely on the sleeve 89 between the bearings 90 and 91 which are secured to the vertical plate 31.

Secured to the lower rope drum 79 are the ends of an additional rope 92 which passes around direction pulleys 93 and 94 mounted in the bearing 95 at the lower end of the cylinder 96 which is secured to the vertical plate 31. The intermediate loop portion is extended around a pulley 83 flexibly mounted at the outer portion of the arm 97 carrying a splitting tool 98.

The arms 87 and 97 are mounted to swing on the same upright axis. By referring to Figs. 3, 7 and 8, it will be seen that the hub of the arm 87 is provided with a downwardly extending hollow shaft 99 and that the hub of the arm 97 is mounted on the lower end of this shaft on the base plate 14. In order to allow for the differences in the lengths of the ropes 80 and 92, or for differences in elasticity thereof, and to secure substantially equal pulling on the ropes, the arm 97 is not keyed directly to the shaft 99 but is provided with a key 100 for arcuate movement along the slot 101, as shown in Fig. 8. The upper arm 87 may therefore be moved forward relatively to the lower arm by reason of the key 100 traveling along the slot 101 but when the key 100 reaches the end of the slot a pull on the upper arm 87 will assist in movement of the lower arm. If the rope 92 should become too slack or disconnected, movement can still be transmitted to the lower arm through the shaft 99 and the key 100. It is preferable, however, to maintain the ropes 80 and 92 taut so as to secure a greater leverage on both of the arms 87 and 97 in movement of the splitting tools along the mine wall. It should be understood that although Fig. 3, which is a sectional elevation on line 3—3 of Fig. 1, shows the splitting tools 88 and 98 on arms 87 and 97, respectively, on the opposite sides of the machine, similar arms and splitting tools are located on the near side of the machine, as viewed in Fig. 2.

In order to move the arms 87 and 97 into their initial positions approximately at right angles to the path of travel of the mining and loading machine, as illustrated in Fig. 1, I have provided an additional rope drum 102 on the vertical shaft 71, as shown in Fig. 3. One end of the rope 103 is connected to the drum 102 and the other end of said rope is connected to another rope drum 104 which is keyed to the vertical shaft 99. Connected to the rope drum 102 is a spur gear 105 which meshes with a spur gear 106 mounted loosely on the vertical shaft 107 in the bearing 108 on the vertical plate 31. The lower side of the spur gear 106 is provided with a clutch element 109 which is adapted to be engaged by a clutch element 110 splined to the shaft 107 adapted to be actuated by the lever 111 so as to effect transmission of power through

the spur gears 112 and 113 to the shaft 107 and thence through the gears 103 and 105 to the rope drum 102. By referring to Fig. 1, it will be seen that the rope 103 is so arranged on the drums 102 and 104 that when these rope drums are operated the vertical shaft 99 will be rotated clockwise to swing the arms 87 and 97 to initial operating positions substantially at right angles to the path of travel of the mining and loading machine, as illustrated in Fig. 1.

While in some instances two sets of splitting tools, one operating along the base of the mine wall and one in elevated position, are provided, I prefer to add a third set adjustable in elevation particularly for operation in mines where the heights of the roofs in mine chambers vary. For this purpose I have shown an upper frame 114 secured to the upper end of the screw-threaded rod 115 and provided with an upper projection 116 adapted to engage the roof of the mine chamber. The screw-threaded rod 115 is movable vertically in the guide cylinder 117 secured to the vertical plate 31. On top of the cylinder 117 is a nut 118 screw-threaded to the rod 115 and provided with a worm gear 119 with which meshes the worm 120 on the shaft 121 which carries the spur gear 122. An electric motor mounted on a bracket 123 secured to the plate 31 is provided with a pinion 124 in mesh with the gear 122. It will thus be seen that by operating the electric motor 125 power may be transmitted to rotate the nut 118 and thereby move the screw-threaded rod 115 up or down along the guide cylinder 117, rotary movement of the rod 115 being permitted by its upper end being journaled to the frame 114.

At the forward end of the plate 31 is mounted a roof jack comprising a screw-threaded rod 126 the upper end of which is serrated at 127 and movable up and down relative to the frame 114. The screw-threaded rod 126 is movable into and along the cylinder 96 but is held against rotation by the spline 128 fitting in the vertical slot 129. At the upper end of the cylinder 96 is mounted a nut 130 threaded on the screw-threaded rod 126 and provided with a worm gear 131 with which meshes a worm 132 adapted to be driven by an electric motor 133, as shown in Fig. 1. The nut 130 is located between the bracket 91 and the cylinder 96 while the screw-threaded rod 126 is guided along the sleeve 89 and the interior of the cylinder 96. The upper end of the rod 126 extends through a bearing sleeve 134 mounted in the forward end of the frame 114.

By referring to Fig. 1, it will be seen that the frame 114 is provided with cross pieces 135 and 136 and is provided with roof jacks at the forward end thereof at opposite sides of the machine, and that there are also roof jacks on opposite sides of the machine for the

intermediate portions of the frame. The frame 114 is also provided with splitting tools 137 each having an arm 138 on opposite sides of the machine, as shown in Fig. 1. The mechanism for operating these splitting tools is illustrated in Fig. 3. At the rear end of the frame 114 is located a rope drum 139 keyed to the upper end of the shaft 140 which is provided with a spline 141 slideable along a slot in the hollow shaft 71. Therefore, when the rope drums 78 and 79 are rotated to exert pulls on the ropes 80 and 92, the rope drum 139 will also be rotated. Secured to the rope drum 139 are the ends of a rope 142 which extends over the direction pulleys 143 and 144 at the forward end of the frame 114. The intermediate loop portion of the rope 142 extends around the pulley 145 mounted on the arm 138, as shown in Fig. 1. The hub of the arm 138 is keyed to the upper end of the shaft 146, as shown in Fig. 3. The shaft 146 extends downwardly from the frame 114 and is provided with a spline 147 which is adapted to slide along the slot in the hollow shaft 99.

It will thus be seen that by initially operating the motors 125 at the opposite sides of the machine, the frame 114 may be projected against the roof of the mine chamber to anchor such frame firmly in position. It is preferable to have the forward roof jacks movable through the forward portions of the frame 114 so that a bending strain will not be put on the frame 114 and so that anchoring of the forward portion of the conveyer frame may be secured independently of the rear roof jack mechanism. This is particularly advantageous where the roof adjacent the working face of the mine wall may be at a somewhat different elevation than the roof where the roof jacks 115 are applied.

In restoring the splitting tools to their initial operating positions where they are approximately at right angles to the path of travel of the mining and loading machine, one rope 103 connected between two rope drums 102 and 104, is sufficient, because when the rope drum 104 is rotated by means of the pull on the rope 103, motion will be transmitted through the shafts 99 and 146 to the arms 97 and 138 as well as to the arm 87. Such restoring movement can easily be effected by rotation of the rope drum 104 on the axis of the shafts 99 and 146, but when the splitting tools are operated arcuately along the mine wall, as illustrated in Fig. 1, greater leverage and therefore more power is secured by connecting the ropes to the outer portions of the arms as illustrated.

In order to further brace the machine during the operation of the splitting devices, particularly when they are operated only on one side of the machine, the diagonal wall jacks 148 and 149 may be provided, as shown in Fig. 1. However, when sufficient space is avail-

able and the splitting devices on opposite sides of the machine may be operated at the same time, the machine will be well balanced without much tendency for the splitting tools on either side of the machine to move or twist the main frame on the floor of the mine chamber. When it is desired to use the splitting tools on one side of the machine, the supplemental conveyer on the opposite side may be swung to a folded position as shown in Fig. 1. This is permitted by reason of the cylinders 117 and 96 having a space below them, as shown in Figs. 2 and 3. Whatever the positions of the lowermost splitting tools may be they are always located in planes above the supplemental conveyers and therefore during transportation of the machine the supplemental conveyers on opposite sides may be swung into folded position and the splitting tools brought to parallel positions at opposite sides of the main conveyer and the uppermost splitting tools let down into comparatively low positions.

It should be noted that the mining and loading machine herein disclosed may be used for mining and loading coal from a mine heading in a comparatively wide mine chamber and this operation is preferred where space is available, on account of the balancing effect due to the mining tools moving toward each other simultaneously, but it should also be understood that the machine may be used in long wall operations by the movement of the splitting tools either on one side or the other of the track on the mine wall adjacent said track.

Fig. 9 illustrates diagrammatically the circuits and connections for the electrically operated roof jacks. When an electric motor of any of said roof jacks is started the reversing switch 150 occupies the full line position whereupon the current will pass from the positive main through the field 151 of the electric motor and thence through the switch blade 152, the switch 153 of the automatic circuit breaker, the magnet 154 of this automatic circuit breaker and thence through the conductor 155, the armature 156 of the electric motor, the fuse 157 and the other switch blade 158 of the switch 150 and finally to the negative main. After this circuit has been closed and the motor operated to project the roof jack into anchoring position, the tightening of the roof jack against the roof will slow down the motor and in its effort to tighten the roof jack more firmly in place, the flow of the current will increase until it will be sufficient to cause the magnet 154 to automatically open the circuit breaker and stop the motor and thus discontinue the operation of the roof jack. When the circuit breaker is operated the circuit to the motor is interrupted at the switch 153 and since the current is then cut off from the motor the latter will stop. When the motors are started they acquire consider-

able momentum because the load operated thereby is comparatively small since only the frame 114 and the parts carried thereby need be lifted toward the roof but as soon as the roof is engaged considerably more power is necessary. This is true with respect to either the forward roof jacks or the rear roof jacks and any of the electric motors therefor. The building up of the momentum assists in firmly securing the roof jacks in position. Therefore, when the roof jacks are to be released from a position of rest, the motors may require more current to start them to overcome the inertia and to loosen or release the roof jacks. In other words, when the roof jacks were tightened in position the motors were still operating and with the benefit of the momentum above referred to, but when the roof jacks are to be released, the motors must start from rest and require more current to effect such release of the roof jacks. It is, therefore, preferable in starting the electric motors to release the roof jacks to throw the reversing switch 150 to the dotted line position shown in Fig. 9 to not only reverse the current through the motor but also to cut out the resistance of the magnet 154 of the automatic circuit breaker and rely only upon the fuse 157 to protect the motor. It will thus be seen that the circuits and connections shown in Fig. 9 will enable the power to the motors to be cut off automatically when the roof jacks are firmly set in anchored positions and when the motors are reversed to release the roof jacks, sufficient electric power may be transmitted to the electric motors to effect such release.

Obviously those skilled in the art may make various changes in the details and arrangements of parts without departing from the spirit and scope of my invention as defined by the claims hereto appended, and I wish, therefore, not to be restricted to the precise construction herein disclosed.

Having thus fully described and shown an embodiment of my invention, what I desire to secure by Letters Patent of the United States, is:

1. In a mining and loading machine, the combination with supporting framework, of coal splitting mechanism mounted on said framework for arcuate movement relatively thereto and along an upright mine wall, means for operating said coal splitting mechanism to dislodge material from said upright mine wall, a conveyer for transferring dislodged material toward loading position, and a supplemental conveyer for moving dislodged material along the base of the mine wall toward the receiving end of said conveyer.

2. In a mining machine, the combination with a supporting frame, of anchoring mechanism therefor to effect an abutment, a plurality of elongated arms mounted on said

frame to swing on upright axes, penetrating wedging tools mounted on the outer ends of said arms in position to penetrate deeply the solid upright coal face and tear the coal therefrom in large pieces over a wide area, and means comprising rope gearing to swing said elongated arms on said upright axes while said frame remains anchored, to operate said tools to effect such dislodgment of the coal from the mine wall.

3. In a mining machine, the combination with a main frame, of a supplemental frame mounted on said main frame for arcuate movement relatively thereto on an upright axis, a plurality of parallel horizontal elongated dislodging tools mounted on said supplemental frame in upright spaced-apart relation in position to dislodge material from the mine wall along the whole upright face between the floor and roof of the mine chamber by parallel bodily lineal movements of said tools by the swinging thereof on such upright axis, and means for operating said dislodging tools by swinging them on such upright axis to cause such tools to penetrate the solid upright face of the coal vein and split portions therefrom over such wide area and in comparatively large lumps.

4. In a mining machine, the combination with a main frame having a forward extension adapted to rest on the floor of a mine chamber, of roof jack mechanism for anchoring such forward extension between the floor and roof of the mine chamber, an upright series of coal splitting tools adapted to penetrate the solid unmined mass and form upright cleavages therein inside of the front upright face thereof to dislodge the coal between the floor and roof in comparatively large lumps, means for supporting said coal splitting tools to swing on an upright axis relatively to said roof jack mechanism, and means mounted on said extension for swinging said splitting tools along arcuate paths of travel while such extension remains anchored by said roof jack.

5. In a mining and loading machine, the combination with a conveyer comprising a stationary bed with transverse flights adapted to travel along the same, of a supplemental conveyer pivoted to one corner of the forward end of said first-named conveyer and extending laterally therefrom, said supplemental conveyer comprising a traveling chain having spaced flights extending outwardly therefrom, means for dislodging material from a mine wall into the range of action of said supplemental conveyer, and means for operating said supplemental conveyer to deliver dislodged material to said first-named conveyer.

6. In a mining and loading machine, the combination with a supporting frame, of a main conveyer mounted thereon, a supplemental conveyer elongated laterally from the

forward end of said main conveyer and adapted to occupy an elongated arcuate position approximately parallel to the arcuate face of the mine wall, and dislodging mechanism 5 mounted on said supporting frame in position for an arcuate dislodging path of travel along the mine wall above said supplemental conveyer.

7. In a mining machine, the combination 10 with a supporting frame, of a pair of coal penetrating wedging tools mounted on said frame for movement in opposite directions toward each other on spaced-apart upright axes, the penetrating end of each tool being 15 farther from its axis of movement than the wedging surfaces receding from said penetrating end, and means for operating said devices by swinging arcuate movements thereof relatively to said frame and in opposite directions toward each other to cause each to penetrate the solid face of a coal vein in its native state and by wedging action tear the coal from such face over a wide area adjacent said dislodging devices.

25 8. In a mining and loading machine, the combination with a supporting frame, of loading apparatus comprising a conveyer on said supporting frame, coal splitting mechanism mounted on said frame at opposite sides 30 of said conveyer, and means for operating said coal splitting mechanism by swinging movements thereof relatively to said frame and in opposite directions toward the forward receiving end of said conveyer.

35 9. In a mining and loading machine, the combination with a supporting frame, of a main conveyer mounted thereon, supplemental conveyers extending laterally from the forward end of said main conveyer and traveling in opposite directions toward the receiving end of said main conveyer, dislodging devices at opposite sides of said main conveyer, and means for operating said dislodging devices by swinging movements thereof in opposite directions toward the receiving 45 end of said conveyer above said supplemental conveyers.

10. In a mining machine, the combination 50 with a main frame, of a supplemental frame pivotally connected to the forward end of said main frame at one side thereof and adapted to be moved into folded position along one lateral side of said main frame, a main conveyer mounted on said main frame, and a supplemental conveyer mounted on said 55 supplemental frame to travel along an arcuate path close to the floor in position to transfer material toward the receiving end of said main conveyer when said supplemental frame is adjusted to a position extending laterally away from the forward end of said main frame.

11. In a mining machine, the combination 60 with a main frame, of a conveyer having superposed portions traveling in opposite di-

rections to and from a forward receiving end of said main frame adapted to rest on the floor of a mine chamber at the base of an arcuate mine wall, a supplemental frame pivotally connected to said main frame at one side of the forward receiving end thereof and adapted to rest on the mine floor and extend arcuately along such arcuate mine wall, and a traveling supplemental conveyer 70 mounted on said supplemental frame to transfer dislodged material along such arcuate mine wall toward the receiving end of said main conveyer.

12. In coal mining and loading apparatus, the combination with a supporting frame, of 80 dislodging mechanism mounted thereon and comprising elongated penetrating wedging tools each adapted to penetrate deeply the solid face of a coal vein and by wedging action split large pieces of coal from the unmined mass over a wide area with a minimum production of fine particles of coal, means comprising rope gearing for operating said dislodging mechanism to form upright cleavages 85 in the unmined mass of coal substantially inside of the front upright face thereof to effect such dislodgment of the coal, and loading apparatus mounted on said frame and having a receiving portion adjacent the range of operation of said dislodging mechanism.

13. In a mining and loading machine, the combination with digging mechanism for effecting upright cleavage of coal from the upright face of an arcuate mine wall from the floor to the roof of the mine chamber, of 90 means for operating said digging mechanism including swinging feeding movement thereof through an arc of approximately ninety degrees, and a conveyer mounted in fixed relation to said digging mechanism with its receiving end below the horizontal path of travel of said digging mechanism.

14. In a mining machine, the combination with a base frame, of an upper movable frame, means for adjusting the elevation of 100 said upper frame and anchoring the same to the roof of the mine chamber, a plurality of splitting tools mounted on said frames, and means for swinging said tools relatively to said frames while the latter are anchored between the floor and roof of the mine chamber.

15. In a mining machine, the combination with a base frame, of a splitting tool mounted 110 thereon for arcuate movement relatively thereto on an upright axis, means on said base frame for swinging said splitting tool, an upper movable frame, an additional splitting tool pivotally connected to said upper frame 120 for swinging movement relatively thereto on an upright axis, roof jack mechanism between said frames for anchoring them between the floor and roof of the mine chamber, and means mounted on said frames for transmitting power to said splitting tools to swing the 125

same relatively to said frames along arcuate paths of travel.

16. In a mining machine, the combination with a roof jack, of means comprising an electric motor for operating said roof jack to anchoring position, and a reversing switch for reversing the current to said motor and increasing the power thereof to release said roof jack.

10 17. In a mining machine, the combination with a jack, of means comprising an electric motor for operating said jack to anchoring position, a resistance in circuit with said motor, and a switch for reversing said motor 75 and for cutting out said resistance to increase the power of said motor to effect release of said jack.

18. In a mining machine, the combination with a jack, of means comprising an electric 20 motor for operating said jack, a circuit breaker connected to said motor to automatically interrupt the flow of current through said motor to stop the same when said jack has been moved to anchoring position, and a 25 switch for reversing said motor to effect the release of said jack.

19. In a mining machine, the combination with a supporting frame, of an abutment 30 adapted to engage an upright wall of the mine chamber, a coal digging and splitting tool, means for mounting said tool on said frame to swing on an upright axis while said abutment resists lateral swerving of said frame, and means comprising rope gearing for exerting 35 a continuous thrust on said splitting tool by swinging the same on said upright axis.

20. In a mining machine, the combination with a supporting frame, of a wall abutment, 40 a dislodging tool adapted to penetrate the solid of the mine vein and tear away the face of the mine vein, and means comprising rope gearing for exerting a continuous forward thrust on said tool away from said wall abutment.

45 21. In a mining machine, the combination with a supporting frame, of wall jacks on the opposite sides of the forward portion of said frame, penetrating wedging devices mounted on said frame for swinging movements in opposite directions, and means for operating said penetrating wedging devices by imparting continuous forward movements thereto to cause the same to act on the coal face while the coal is in its native state and dislodge coal directly from the unmined mass over a wide area of said coal face while said wall jacks act as abutments.

50 22. In a mining machine, the combination with a supporting frame, of wall jacks on opposite sides thereof, a plurality of spaced-apart penetrating wedging tools mounted on said frame to swing in a predetermined direction relatively thereto, another set of spaced-apart penetrating wedging tools mounted on said frame to swing relatively

thereto in the opposite direction, and means for operating said tools by imparting continuous forward sweeping movements thereto to cause the tools to act on the coal in its native bed and slice off the entire working 70 faces from the mine vein.

23. In a mining and loading machine, the combination with a supporting frame, of dislodging mechanism mounted thereon and adapted to engage the solid coal of a mine vein 75 and by wedging action tear the coal from the face of the mine vein, means comprising rope gearing for operating said dislodging mechanism, means adapted to engage a wall of the mine chamber to resist the backward 80 thrust during the operation of said dislodging mechanism, and loading apparatus for receiving the dislodged coal from the mine wall and conveying it toward loading position. 85

24. In a mining and loading machine, the combination with supporting framework, of coal splitting mechanism mounted on said framework for movement relatively thereto along an upright mine wall, means for operating said coal splitting mechanism to dislodge material from said upright mine wall, a main conveyer for transferring dislodged material toward loading position, and a supplemental conveyer operable independently 90 of said coal splitting mechanism for moving dislodged material along the base of the mine wall toward the receiving end of said conveyer. 95

25. In a mining machine, the combination with a supporting frame, of multiple penetrating and coal splitting mechanism mounted on said frame for swinging movement on an upright axis along an upright arcuate coal face and comprising a plurality of spaced-apart elongated radial arms with penetrating 100 wedging tools projecting substantially at right angles from the outer ends of said arms, and power-operated mechanism for moving said multiple penetrating and coal splitting 105 mechanism along such upright arcuate coal face to cause said penetrating wedging tools to dislodge the coal in large pieces. 110

26. In a mining and loading machine, the combination with a supporting frame, of a main conveyer mounted thereon, a flat supplemental flight conveyer elongated laterally from the forward end of said main conveyer and comprising a flat plate with an elongated 115 scooping edge adapted to extend along the floor laterally from the main conveyer, and dislodging mechanism mounted on said supporting frame in position for operation adjacent said main and supplemental conveyers to dislodge the material for said supplemental conveyer to move it toward said main conveyer. 120

27. In a mining and loading machine, the combination with a supporting frame, of a main conveyer mounted thereon, a supple- 125

mental conveyer connected to said main conveyer and adapted throughout substantially its entire length to lie horizontally flat on the floor adjacent said frame, and means mounted on said frame in position to dislodge the mineral from the mine vein on the same side as that on which the supplemental conveyer is located, such mineral being dislodged into position to be gathered by said supplemental conveyer and transferred toward said main conveyer.

28. In a mining and loading machine, the combination with a supporting frame, of a main conveyer thereon, a pair of elongated supplemental traveling flight conveyers each comprising a thin floor plate with the traveling flights on top of the same, said supplemental conveyers branching in opposite directions from the forward end of said main conveyer and each adapted to transfer material along its floor plate toward the receiving end of said main conveyer, and means mounted on said frame in position to dislodge material adjacent said conveyers for collection thereby.

29. In a mining and loading machine, the combination with a supporting frame, of a main traveling conveyer mounted thereon, a pair of supplemental traveling conveyers branching laterally from the forward end of said main conveyer, means for dislodging material into the range of said branching conveyers for delivery by the latter toward the receiving end of said main conveyer, and a scoop on the receiving end of said main conveyer to collect from the floor onto the main conveyer the material gathered by said supplemental conveyers.

30. In a mining and loading machine, the combination with a supporting frame, of a main conveyer mounted thereon, a roof jack at one side of the forward end portion of said conveyer for anchoring said frame, and a supplemental elongated conveyer pivoted to the forward end of said main conveyer and foldable to a position under said roof jack.

31. In a mining and loading machine, the combination with a supporting frame, of a main conveyer mounted thereon, spaced apart roof jacks at the sides of the forward end portion of said conveyer, a pair of flat elongated supplemental conveyers pivoted to the forward end of said main conveyer and foldable under said roof jacks, and means for operating said conveyers.

32. In a mining and loading machine, the combination with a main conveyer, of a thin flat plate to constitute an elongated receiving portion adapted to extend along the base of a mine wall at the mine floor, and a traveling supplemental conveyer on top of said thin flat plate to slide dislodged material along the latter toward the receiving end of said main conveyer.

33. In a coal mining and loading machine,

the combination with a supporting frame, of a traveling conveyer mounted above the longitudinal length of said supporting frame and having its forward receiving position adapted to be located adjacent the base of the mine wall, dislodging mechanism comprising a plurality of penetrating wedging tools arranged in an upright series for operation along an upright arcuate coal face, and means for operating said penetrating wedging tools by swinging the same on an upright axis from a position remote from the receiving end of said conveyer to a position near the same.

34. In a mining and loading machine, the combination with a supporting frame, of a conveyer mounted thereon, roof jack mechanism for the forward end portion of said frame, an upper movable frame, dislodging mechanism movable with said upper frame for adjustment in elevation, and roof jack mechanism for said upper frame for anchoring the latter independently of said first-named roof jack mechanism.

35. In a mining machine, the combination with a jack, of means comprising an electric motor for operating said jack, a circuit breaker comprising an electro-magnet in series with said motor, and a reversing switch for said motor and connected to cut out said electro-magnet when the jack is to be released by reversal of the motor.

36. In a mining machine, the combination with a supporting frame, of an abutment therefor, a plurality of penetrating wedging tools each adapted to penetrate the solid upright coal face and by wedging action split the coal from the unmoved mass, a plurality of supports one for each of said tools with the space between adjacent supports free and unobstructed, means for mounting said supports on said frame for swinging movement relatively thereto while said abutment resists movement of said frame, and means for moving said supports to exert continuous thrusts on said tools to cause the latter to split the coal from the upright coal face in large pieces over a wide area.

37. In a mining machine, the combination with a supporting frame, of an abutment, dislodging mechanism comprising a plurality of penetrating wedging tools and individual supports therefor with the space between each support and the next adjacent one entirely free and unobstructed to afford freedom of deep penetration of the tools into the solid upright face of the mine vein, and means for moving said supports to exert continuous forward thrusts on said tools while movement of said frame is resisted by said abutment.

38. In a mining machine, the combination with a main frame, of a main conveyer on said main frame with its receiving end at the surface from which the material is to be

- loaded, a supplemental frame pivotally connected to the forward end of said main frame at one side thereof and at the floor, said supplemental frame comprising an elongated receiving edge adapted to occupy a position adjacent the mine floor to facilitate movement of the dislodged material from the floor onto said supplemental frame, and a flight conveyer on said supplemental frame in position to travel along the elongated receiving edge close to the floor to transfer said material toward the receiving end of said main conveyer at the floor when said supplemental frame is adjusted to a position extending laterally away from the forward end of said main frame.
39. In a mining machine, the combination with a main frame, of a main conveyer thereon with its forward receiving end adapted to rest on the floor of a mine chamber at the base of an arcuate mine wall, a supplemental frame pivotally connected to said main frame at one side of the forward receiving end thereof, and adapted to rest on the mine floor and extend arcuately along said arcuate mine wall, said supplemental frame having an elongated arcuate receiving edge adapted to rest on the mine floor near the arcuate mine wall, and a traveling flight conveyer on said supplemental frame in position to operate along said elongated arcuate edge toward the receiving end of said main conveyer to deliver material to the latter.
40. In a mining machine, the combination with a supporting frame, of a pair of coal penetrating wedging devices mounted on said frame for either independent or simultaneous movement in opposite directions toward each other, means for operating said devices by swinging arcuate movements thereof relatively to said frame and in opposite directions toward each other, and means for controlling said movements so as to be either independent of each other or simultaneous to cause each to penetrate the solid face of the coal vein in its native state and by wedging action tear the coal from such face over a wide area adjacent such dislodging devices.
41. In a mining machine, the combination with a supporting frame, of a pair of multiple coal penetrating wedging mechanisms mounted on said frame for movement relatively thereto in opposite directions, each of said multiple coal penetrating mechanisms comprising an upright series of spaced-apart penetrating wedging tools and spaced supports therefor, and means for operating said multiple coal penetrating mechanisms by swinging arcuate movements thereof relatively to said frame and in opposite directions toward each other to cause each upright series of tools to penetrate the solid face of the coal vein in its native state and by wedging actions tear the coal in large pieces from such face over a wide area at and adjacent said tools.
42. In a mining machine, the combination with a main frame, of a main conveyer thereon having superposed parts traveling in opposite directions, a supplemental frame pivotally connected to the forward end of said main frame at one lateral side thereof and adapted to be moved into folded position along one side of said main frame while retaining the space above said main conveyer free and unobstructed, and a supplemental conveyer mounted on said supplemental frame to travel a path close to the floor in position to transfer material to a position in front of the receiving end of said main conveyer when said supplemental conveyer is adjusted to a position extending laterally away from the forward end of said main frame.

In testimony whereof I have signed my name to this specification on this 19th day of June, A. D. 1920.

EDMUND C. MORGAN.
